(57) CLAIM

The ornamental design for a golf club turf repair device, as shown and described.

DESCRIPTION

FIG. 1 is a front view of a golf club turf repair device as constructed in accordance with the present invention with the rear view being a mirror image thereof;

FIG. 2 is a side view with the opposite side being a mirror image thereof;

FIG. 3 is a bottom end view thereof;

FIG. 4 is a top end view thereof;

FIG. 5 is a fragmentary perspective view taken generally from the top end thereof; and,

FIG. 6 is a fragmentary perspective view taken generally from the bottom end thereof.

The shaft is shown broken away in FIGS. 5 and 6 for ease of illustration.
